HEDDLE BAR SUPPORTING MEANS

Ralph Ragan, Atlanta, Ga., assignor to Steel Heddle Manufacturing Company, Philadelphia, Pa., a corporation of Pennsylvania

Application December 6, 1932, Serial No. 645,904

16 Claims. (Cl. 139—92)

This invention relates to supports for the heddle bars of the heddle frames of looms.

One of the principal objects of the invention is to provide a support and locking means for the 5 heddle bars which is simple and inexpensive, and which at the same time will be efficient in operation.

Another object of the invention is to provide a support and locking means in which a pronged washer is used for locking the heddle bars in position, the construction and arrangement being such that the pressure applied on the prongs of the washer when the latter is in position for locking the bars, forces the bars inwardly against the heddle support so as to maintain them jammed against the latter throughout their width.

A further object of the invention is to provide a spring pressed locking device in conjunction with a locking nut, the spring acting not only to normally maintain the heddle bars in locked position, but also to bind the nut in position for locking the bars in place against the support.

Another object is to provide a heddle bar support and locking means in which the spring which normally maintains the bars in locked position also holds the center brace in position against the support.

Further objects of the invention will hereinafter appear as the description proceeds.

In the drawing, in which I have shown for illustrative purposes one of the forms that the invention may take, and modifications thereof;

Fig. 1 represents a fragmentary view in elevation, partly in section of a portion of a heddle frame showing my invention applied thereto, some of the heddles being shown in position on the heddle bars, and the locking nut being shown in open or raised position.

Fig. 2 represents a similar view, the heddles being omitted for clearness of illustration, the locking nut being shown in closed or lowered position.

Fig. 3 represents a sectional view at right angles to Fig. 1 taken on the line 3—3 thereof looking in the direction indicated by the arrows, the heddles being omitted.

Fig. 4 represents a view in section taken on the line 4—4 of Fig. 1 looking in the direction of the arrows, the heddles and the center brace being omitted.

Fig. 5 represents a plan view of the spring.

Fig. 6 represents a horizontal sectional view on the line 6—6 of Fig. 4.

Fig. 7 represents a view similar to Fig. 4 of

a modified form of the invention, the locking nut being shown in lowered position.

Fig. 8 represents a view similar to Fig. 4 of a form of the invention that may be utilized in connection with a lock for a single heddle bar support. 5

Figs. 9 and 10 are views similar to Fig. 1, of modifications.

Referring more particularly to the drawing, I have illustrated the invention assembled in conjunction with the top rail of a heddle frame, it being understood that a similar arrangement may be used in connection with the lower rail except that it is in reversed position. The rail is indicated at 5, the heddle bars at 6, the upper ends 10 of a number of heddles at 7, the center brace at 8, and the heddle bar support at 9. The latter may be in the form of a bolt flattened at its inner end and provided with beveled shoulders 10 against which the inner or lower edges of the 15 heddle bars 6 rest when the bars are in position on the support. The inclination of the shoulders is such as to wedge or cam the bars against the support. The bolt is suitably mounted on the rail, and for this purpose may be threaded 20 through a metal plate 11 attached by means of screws 12 to the inner face of the rail, may pass through an opening in the rail, and on the upper face thereof may receive a winged nut 13 for tightening it in position and preventing it 25 from turning in the plate 11. The nut may bear against a suitable washer 14 which may be in the form of a lock washer if desired. 30

Slidable longitudinally of the support 9 is a washer 15 having the prongs or arms 16 depending therefrom. The lower ends of the prongs are bent inwardly into alignment with the shoulders 10 and into close association with the edges of the flattened portion of the bolt, so that while the washer is free to slide up and down on the bolt, 35 it cannot turn thereon to any great extent since the clearance between the lower ends of the prongs and the edges of the flattened portion of the bolt is so small (see Fig. 7) that the prongs will bind against the bolt before the washer turns to any 40 considerable extent.

The lower ends of the prongs are recessed as at 17, and the curvature of the inner ends of the recesses is the same as the curvature of the natural rolled edges of the heddle bars, so that the lower 50 ends of the prongs fit the heddle bars very snugly. Similarly the shoulders 10 at their junction with the support are likewise rounded to accord with the natural rolled edges of the heddle bars.

It will be observed that due to the angularity 55

of the prongs of the washer, any pressure tending to move the washer downwardly when the bars are in position on the support, will also tend to flex the arms and force their lower ends inwardly toward the edges of the support, and thus bind the bars against such edges. It will also be noted that by having the locking arms or prongs of the washer in the same vertical plane as the locking shoulders of the support the lateral width of the bearing surface of the flattened portion of the support, and of the prongs and shoulders can be relatively great without unduly increasing the distance that separates the heddles adjacent the heddle bar support. In other words maximum supporting area for the heddle bars with minimum width of such area is obtained. This is of importance, when it is understood that if the width between the heddles adjacent the lock is too great the heddles will be separated so much that reed marks will result in the cloth.

In order to maintain the locking washer normally in position to hold the bars in place, I utilize a leaf spring 18 anchored at its upper end to the plate 11 by one of the screws 12. At its lower end the spring is forked at 19 so as to straddle the support 9, and rest upon the upper face of the pronged washer 15. The spring thus constantly urges the washer downwardly. A center prong 20 is also formed on the spring and extends downwardly to engage against the upper end of the center brace 8 so as to maintain such brace against the support 9. The brace is recessed to receive the heddle bars 6 and it will be understood that while only the upper end of the brace is shown, the other or lower end may be similarly formed. The forked end of the spring, in addition to urging the locking washer downwardly, by straddling the support 9, keeps the spring from shifting sidewise and thus prevents fouling an adjacent frame.

While the spring may, particularly in light frames, be sufficiently strong to maintain the locking washer in locking engagement with the heddle bars I may, especially in heavy frames, use additional means for positively binding the locking washer in position. This means takes the form of a locking nut 21 which is threaded on the support or bolt 9 above the locking washer and the forked end of the spring. By turning the nut downwardly into the position indicated in Fig. 2, for instance, the locking washer is forced downwardly to bring the prongs 16 thereof into tight binding engagement with the bars 6 so as to rigidly hold the latter throughout their width against the bearing faces of the support. This movement of the nut will flex the spring 18 substantially as indicated in Fig. 2 so that the latter will bind the nut and act as a locking means to prevent accidental unscrewing thereof. Thus the bars will be rigidly locked in position so that they cannot vibrate, wear will be prevented, and crystallization or weakening of the metal of the bars will be prevented since they will be held immovable against the support. Furthermore the action of the prongs in binding the bars throughout their width against the support will add the strength of the cross sectional area of the bars to the frame members to thus additionally brace the frame.

It will be noted that the plate 11 not only strengthens the frame at the point where the support is mounted, but acts as a means for adjusting the vertical position of the support, and in conjunction with the wing nut locks the support in position.

When it is desired to release the heddle bars,

the nut is unscrewed to move it upwardly on the support, whereupon the washer may be moved upwardly against the tension of the spring until the lower ends of the prongs clear the bars, then the latter may be moved out of engagement with the shoulders 10 and away from the support so as to allow the heddles to be shifted along the bars.

In Fig. 7 I have shown a modification of the invention which is applicable to a support in which the bars are held in staggered relation. In this form of the invention one of the shoulders 10^a is lower than the opposite shoulder 10^b and one of the prongs 16^a of the locking washer 15^a is lengthened so as to bring it into engagement with the upper edge of the lower heddle bar 6^a. The same formation of spring and locking nut, 18 and 21 respectively, may be used as before.

I have shown the invention as applied to a double heddle bar support, but it will be understood that it can be applied equally as well to a single heddle bar support. In the latter event the locking washer may be supplied with only one prong instead of two, and the support may have one shoulder for receiving the heddle bar instead of two. Such an arrangement is shown in Fig. 8, in which 15^b is the washer having the single prong 16^b, 9^b is the support having the single shoulder 10^c, and 6^b is the heddle bar. The same spring and locking nut may be used as before.

If desired a spiral spring such as 22 may be utilized instead of the spring 18, in which case it may be mounted on the heddle bar support 9 above the washer so as to bear on the latter, as illustrated in Fig. 9. In this case I may use a washer 15^c having another prong 23, in addition to the prongs 16^c which engage the heddle bars, adapted to normally engage the center brace 8 to retain it against the support. Or, I may utilize a second washer 23' mounted above the washer 15 and beneath the spring, as in Fig. 10, the second washer having a lip 24 adapted to retain the center brace in position. It will be understood that either of these constructions may be used with the double heddle bar support, whether staggered or not, and also with the single heddle bar support.

The foregoing description has been given for purposes of clearness of understanding of the invention and of the particular embodiments thereof chosen for illustrative purposes, but no undue limitations should be deduced therefrom as the claims should be construed as broadly as permissible in view of the prior art.

I claim:

1. In a loom heddle frame, a heddle bar upon which the heddles are mounted, a support for the heddle bar intermediate its ends, said support having a shoulder for receiving the heddle bar, a washer slidably mounted on the support and having a prong adapted to engage the heddle bar thereby to hold it in position on the support, and positive locking means on the support adapted to hold the washer in position to cause the prong thereof to bind the heddle bar positively in fixed position.

2. In a loom heddle frame, a heddle bar upon which the heddles are mounted, a support for the heddle bar intermediate its ends, said support having a shoulder for receiving the heddle bar, a washer slidably mounted on the support and having a prong adapted to engage the heddle bar thereby to hold it in position on the support, and a locking nut threaded on the support and adapted to be advanced thereon to

hold the washer in position to cause the prong thereof to bind the heddle bar positively in fixed position.

3. In a loom heddle frame, a heddle bar upon which the heddles are mounted, a support for the heddle bar intermediate its ends, said support having a shoulder for receiving the heddle bar, a washer slidably mounted on the support and having a prong adapted to engage the heddle bar thereby to hold it in position on the support, a spring having a portion bearing against the washer to urge it toward the heddle bar, and positive locking means on the support adapted to hold the washer in position to cause the prong thereof to bind the heddle bar positively in fixed position.

4. In a loom heddle frame, a heddle bar upon which the heddles are mounted, a support for the heddle bar intermediate its ends, said support having a shoulder for receiving the heddle bar, a washer slidably mounted on the support and having a prong adapted to engage the heddle bar thereby to hold it in position on the support, a spring having a portion bearing against the washer to urge it toward the heddle bar, and a locking nut threaded on the support and adapted to be advanced thereon to hold the washer in position to cause the prong thereof to bind the heddle bar positively in fixed position.

30 5. In a loom heddle frame, a heddle bar upon which the heddles are mounted, a support for the heddle bar having a shoulder for receiving the heddle bar, a washer slidably mounted on the support and having a prong adapted to engage the heddle bar thereby to hold it in position on the support, a leaf spring secured at one end to a fixed portion of the frame and having its other end forked and straddling the support, said forked end bearing against the washer to urge it toward the heddle bar, and a locking nut threaded on the support and adapted to be advanced thereon to hold the washer in position to cause the prong thereof to bind the heddle bar positively.

45 6. In a loom heddle frame, a heddle bar upon which the heddles are mounted, a center brace, a support for the heddle bar having a shoulder for receiving the heddle bar, a washer slidably mounted on the support and having a prong adapted to engage the heddle bar thereby to hold it in position on the support, and a spring having a portion bearing against the washer to urge it toward the heddle bar, one of the members having a depending prong engaging the center brace to hold it in position adjacent the support.

55 7. In a loom heddle frame, a heddle bar upon which the heddles are mounted, a center brace, a support for the heddle bar having a shoulder for receiving the heddle bar, a washer slidably mounted on the support and having a prong adapted to engage the heddle bar thereby to hold it in position on the support, a spring having a portion bearing against the washer to urge it toward the heddle bar, one of the members having a depending prong engaging the center brace to hold it in position adjacent the support, and locking means on the support adapted to hold the washer in position to cause the prong thereof to bind the heddle bar positively.

70 8. In a loom heddle frame, a heddle bar upon which the heddles are mounted, a center brace, a support for the heddle bar having a shoulder for receiving the heddle bar, a washer slidably mounted on the support and having a prong

adapted to engage the heddle bar thereby to hold it in position on the support, a spring having a portion bearing against the washer to urge it toward the heddle bar, one of the members having a depending prong engaging the center brace to hold it in position adjacent the support, and a locking nut threaded on the support and adapted to be advanced thereon to hold the washer in position to cause the prong thereof to bind the heddle bar positively.

10 9. In a loom heddle frame, a heddle bar upon which the heddles are mounted, a center brace, a support for the heddle bar having a shoulder for receiving the heddle bar, a washer slidably mounted on the support and having a prong adapted to engage the heddle bar thereby to hold it in position on the support, a leaf spring secured at one end to a fixed portion of the frame and having its other end bearing against the washer to urge it toward the heddle bar, one of the members having a depending prong engaging the center brace to hold it in position adjacent the support, and a locking nut threaded on the support and adapted to be advanced thereon to hold the washer in position to cause the prong thereof to bind the heddle bar positively.

20 10. In a loom heddle frame, a heddle bar upon which the heddles are mounted, a center brace, a support for the heddle bar having a shoulder for receiving the heddle bar, a washer slidably mounted on the support and having a prong adapted to engage the heddle bar thereby to hold it in position on the support, a spring having a portion bearing against the washer to urge it toward the heddle bar, said spring also having an extension engaging the center brace to hold it in position adjacent the support, and a locking nut threaded on the support and adapted to be advanced thereon to hold the washer in position to cause the prong thereof to bind the heddle bar positively.

30 11. In a loom heddle frame, a heddle bar upon which the heddles are mounted, a center brace, a support for the heddle bar having a shoulder for receiving the heddle bar, a washer slidably mounted on the support and having a prong adapted to engage the heddle bar thereby to hold it in position on the support, a leaf spring secured at one end to a fixed portion of the frame and having its other end forked and straddling the support, said forked end bearing against the washer to urge it toward the heddle bar, said spring also having a depending prong engaging the center brace to hold it in position adjacent the support, and a locking nut threaded on the support and adapted to be advanced thereon to hold the washer in position to cause the prong thereof to bind the heddle bar positively.

40 12. In a loom heddle frame, a heddle bar upon which the heddles are mounted, a support for the heddle bar intermediate its ends, said support having a shoulder for receiving the heddle bar, the said support being threaded over a portion of its length, and a lock nut movable on said threaded portion for holding said heddle bar in positive locked position against said shoulder.

50 13. In a loom heddle frame, a heddle bar upon which the heddles are mounted, a support for the heddle bar intermediate its ends, said support having a shoulder for receiving the heddle bar, a member movable on said support having a portion bearing against the heddle bar, and a lock nut bearing against said movable member for holding said heddle bar in positive locked position against said shoulder.

60 14. In a loom heddle frame, a heddle bar upon

which the heddles are mounted, a support for the in contact with said shoulder including a lock, heddle bar intermediate its ends, said support nut movable on said threaded portion, having a shoulder for receiving the heddle bar, means for holding said heddle bar in contact with said shoulder, and a locking member movable along said support to maintain said holding means in fixed position.

15. In a loom heddle frame, a heddle bar upon which the heddles are mounted, a support for the heddle bar intermediate its ends, said support having a shoulder for receiving the heddle bar, the said support being threaded over a portion of its length, and means for locking said heddle bar

16. In a loom heddle frame, a heddle bar upon which the heddles are mounted, a support for the heddle bar intermediate its ends, said support having a shoulder for receiving the heddle bar, and means for clamping said heddle bar in positive locked position in contact with said shoulder, said means including a non-resilient member movable along said support to a position to effect said clamping.
